United States Patent Office

Des. 199,052
Patented Sept. 8, 1964

199,052

RESIDENCE

Robert E. Schwartz, 417 Jerome, Midland, Mich.

Filed May 6, 1963, Ser. No. 74,775

Term of patent 14 years

(Cl. D13—1)

Fig. 5

Fig. 6

Fig. 7

FIG. 1 is a front view of the residence of the present invention.

FIG. 2 is a rear view of the residence of the present invention.

FIG. 3 is a side view of the side opposite the garage of the residence of the present invention.

FIG. 4 is a side view of the garage side of the residence of the present invention.

FIG. 5 is an isometric view of the court in the center of the residence of the present invention.

FIG. 6 is another isometric view taken from the opposite corner from that of FIG. 5 of the court of the residence of the present invention.

FIG. 7 is a top view of the residence of the present invention showing the location of the court.

For convenience of illustration, only parts of the brick surfaces have been shown in the several views on the drawing. It is to be understood that these surfaces continue throughout the plane areas shown.

I claim:

The ornamental design for a residence, as shown and described.
